DRY CLEANSING UNIT

Carl Dahlberg, Duluth, Minn.

Application January 11, 1940, Serial No. 313,418

2 Claims. (Cl. 68—5)

This invention relates to apparatus for and method of cleansing garments and has special reference to such particularly adapted for use in the cleansing of various types of fabric such as silk, flannel, velvet, mohair, or the like.

It is well known in the art that the application of various solvents necessary in the removal of spots from different types of fabric is apt to leave a discolored area about the location of the spot and that the same is very difficult of removal in order to completely restore the surrounding surface of the garment, and to quickly care for and effectively remove such is one of the principal objects of the instant invention.

Another object is that of the specially convenient arrangement of parts in the unit so that all portions of a garment may be cleansed with the least possible effort, for example, not only that of removing spots from certain portions of the garment, but in the cleansing of cuffs, pockets, etc., with the least handling of the garment.

Other objects and advantages of the invention will appear in the following description thereof.

Referring now to the accompanying drawing, forming part of this application, and wherein like reference characters indicate like parts:

Figure 1 is a side elevation, partly broken away and showing portions thereof in section, of a complete unit embodying the invention.

Figure 2 is a top plan view of Figure 1.

Figure 3 is an enlarged sectional view of the air discharge distributing valve.

Figure 4 is an enlarged side elevation of a preferred form of suction control valve.

Figure 5 is a section on the line 5—5, Figure 4, though partly in elevation.

Figure 6 is a side elevation of a novel form of intake nozzle.

Figure 7 is a top plan view of Figure 6.

It is well known that much effort and money has been expended in an attempt to provide a convenient unit of this type, and that it is old in the art to provide a receptacle upon a suitable support to which a garment may be applied and suction formed through such receptacle simultaneously with the application of a solvent or washing material.

In the drawing, 1 represents the main body portion of the apparatus which is preferably of vertically elongated rectangular form, having a forwardly extending base member 2 of considerably less height but of hollow construction, providing a chamber 3 therein, and the body portion 1 is also of hollow construction, provid-

ing the chamber 4 throughout same. The top 7 of said body portion forms a shelf for use as a suitable support for bottles, jars, or cans, containing material necessary in the conduct of such cleansing service.

Upwardly from this main body portion is a reduced preferably rectangular housing indicated at 8 in which is contained the necessary pipe connections for water, steam, and air, as suggested at 9 for use in the apparatus. A hollow shelf 15 is installed on this upwardly extending housing 8 and this shelf is provided with any suitable form of pipe connection as at 6 for maintaining heat as by water or steam throughout the shelf so that upon the shelf may be supported small receptacles such as bottles or the like having cleansing material which it is desired to keep warm during the period of operation of the machine. Extending forwardly from the upper extremity of the housing 8 is the tubular conduit 10, one end of which is connected through the extension downwardly into the chamber 4, the outermost end terminating in a suitable nozzle 11 controlled as by the butterfly valve 12 for the optional attachment of a hose or the like. Just rearwardly of this terminal nozzle 11 and carried by the conduit 10 is the depending adjustable light unit indicated at 13, a suitable connection for which is shown at 14 leading rearwardly to the upright portion of the unit.

At the upper front face of the body portion 1 is a somewhat similar pipe terminal indicated at 16 for optional application of a suction hose or the like, it being provided with a suitable control valve.

Just below the connection 16 is attached the forwardly extending board or work table 17, it being adjacent the body portion preferably of the full width thereof and gradually narrowing 40 towards the opposite end for convenience in the application of various types of garments to be operated upon. Approximately centrally of this board is an upwardly extending valve controlled extension 18, to which any type of screened opening or other instrumentality may be applied as at 19, and upon which the garment to be treated is placed. The pipe for such connection is indicated at 20 and leads backwardly beneath the 45 table or board 17 into the chamber 4 and preferably downwardly within said chamber as at 21.

Upon the front face of the body portion 1 and intermediate of the board 17 and the base extension 2 is attached a suitable centrifugal suction unit 22 communicating with the chamber 4

and discharging through the conduit 23 into the chamber 3, one outer wall of which is provided with a filtered or screened opening to the surrounding atmosphere, as at 24.

Upon the upper outer edge of the base extension 2 is mounted in any suitable manner the power unit or motor 25 for driving of the suction element 22 as by any form of suitable belt 26 or the like, and from the armature of this same motor as by the belt 27 is driven a countershaft 28 supported from the under side of the board 17 and extending within the box like receptacle 29, where it is provided with any suitable arrangement of rotary brushes indicated at 30. Into this receptacle the pockets for example of a garment may be extended and have suction as well as brushing motion applied thereto and be thoroughly cleansed.

To this receptacle 29 is applied the pipe 31 leading to the pipe 32 which connects through the side wall of the body portion 1 to the chamber 4 wherein constant suction is applied or semi-vacuum formed by the unit 22 when in operation.

It is not deemed essential to illustrate in detail means for optional application of power from the motor 25 to the shaft 28, but suffice it to say that any suitable form of fixed and idler pulley 5 may be attached to said shaft and controlled by a suitable lever indicated at 33 supported upon the under side of the board 17, and which lever is attached in any desired manner to the valve 58 so that it is opened when the shaft 30 is set in motion and closed when the shaft is stopped.

An additional work shelf or board is illustrated at 34 and shown as extending from one side of the body portion 1 at right angles to the board 17 and considerably lower than said board, this table or board 34 being specifically for the support of a valve controlled cuff cleansing nozzle indicated at 35 which communicates as by the pipes 36 and 37 with the intake pipe 32, as clearly illustrated.

It is quite obvious that such arrangement of work tables or boards is very handy in the manipulation of single garments having pockets and cuffs therein, as the elements for cleansing same are in ideal juxtaposition for such operation.

Furthermore an additional feature is provided in that a suitable valve controlled hose connection is illustrated at 38 to the discharge pipe 39 of the suction unit 22 intermediate of said unit and the conduit 23; this pipe 39 being cylindrical in shape and disposed horizontally at approximately the level of the shelf or work table 34. There is a novel selective connection here provided in that at the outer terminus of the somewhat enlarged pipe 39 is provided a half cylindrical rotatable valve, indicated at 40, Fig. 3, which controls the discharge from the suction unit 22. This half cylindrical valve is controlled by the stem 41 extending outwardly through the end of the pipe 39 and provided with the suitable hand knob 42 for the convenient rotation of same. The valve is disposed directly intermediate of the opening into the connection 43 of the hose 38 and the upper end of the conduit 23 so that by the turning of the valve 40 air pressure may be had either in the hose 38 or through the conduit 23 into the chamber 3, thus providing convenient means for compressed air discharge through the hand manipulated nozzle 44.

An additional feature of this connection is that provision is made for the use of steam in conjunction with such compressed air supply, and

to this end a lateral connection indicated at 45 is shown upon the elbow of the hose connection 38, and which connection may be controlled as by a valve shown at 47, conveniently located in any desired manner and placed on the extension 8 of the unit, and it is found particularly advantageous to have the steam hose 45 extend substantially the full length of the hose connection 38 so that as nearly live steam as possible may be had at the nozzle 44 when desired.

Still another convenient feature especially adapted for use upon a unit is that of the control valves, a number of which are employed in the unit, and the details, for example of the one shown at 12, are clearly illustrated in Figures 4 and 5 of the drawing, wherein the body portion of the valve is indicated as being internally screw-threaded at one end for application to the pipe 10, and at the other end tapered as at 11 for selective application of a suitable intake hose such as shown at 36. To one side of the body portion 12 is formed a somewhat enlarged lateral extension, flattened externally as at 48, and within which flattened face is formed the circular depression indicated at 49, having a shaft 50 extending axially therethrough and transverse the body portion of the valve 12. Upon this shaft 50 is mounted a common butterfly valve 51 for opening or closing communication to the pipe 10 when the shaft 50 is rotated.

Upon the end of the shaft 50 which protrudes through and into the opening 49 is fixed the sector shaped cam 52, and from adjacent one edge of which protrudes outwardly the pin 53 to which is attached the operating lever 54. Attached to this pin 53 intermediate of the cam and the lever is one end of the contractile helical spring 55, while its opposite end is fastened to a pin 56 for example protruding outwardly from the larger sector shaped fixed portion 57 within the opening 49.

By viewing Figure 4 of the drawing, it is quite apparent that when the lever 54 is in the position there shown the same will be normally held in such position by the contractile energy of the spring 55, and in which position it is desired to have the butterfly valve 51 in closed position transverse the bore of the valve, whereas when the lever is thrown to its opposite rotative position the valve will be wide open and the opposite edge of the sector 52 engage the opposite edge of the fixed section 57, thus limiting the movement of the valve intermediate of its open and closed positions.

In Figures 6 and 7 is illustrated a modified form of nozzle, particularly advantageous in removing a spot from velvet or the like and in which the garment is suspended over a principal rectangularly shaped bell-mouth vessel indicated at 60 having a flat shelf like seat wholly about same and from which seat upwardly protrude a group of closely installed fine wires, such as found in carding cloth, indicated at 61, covering the entire flattened surface so that when a garment or cloth is placed thereover the same will not contact any smooth surface not subjected to air currents passing thereabouts, nor move during the cleansing operation, and thus eliminate any possibility of leaving marks about the area confined to the cleansing process.

Having thus described my invention, what I claim and desire to secure by Letters Patent, is:

1. In a dry cleansing and spotting machine having means for creating a vacuum therein and a steam and air supply, a suction nozzle connect-

ed with said vacuum and adapted to support a soiled portion of a garment thereon and suck air therethrough, a flexible air hose connected with said air supply, a relatively small flexible steam hose connected with said steam supply and extending through said air hose, an exhaust nozzle on the terminous of said air hose through which combined steam and air may be directed to the side of said garment opposite said suction

through said garment and into said suction nozzle.

2. In a dry cleansing spotting machine having means for creating a suction therein, a suction nozzle connected with said vacuum, and carding material supported about the edges of said nozzle and providing means for immovably supporting a portion of a garment over said suction nozzle.

CARL DAHLBERG.
